UNITED STATES PATENT OFFICE

JAMES C. TRAVILLA, JR., OF PHILADELPHIA, PENNSYLVANIA, ASSIGNOR TO GENERAL STEEL CASTINGS CORPORATION, OF GRANITE CITY, ILLINOIS, A CORPORATION OF DELAWARE

RAILWAY TRUCK CENTERING DEVICE

Application filed February 2, 1931. Serial No. 513,036.

My invention relates to railway rolling stock and consists particularly in a novel renewable rocker centering device for use in locomotives, tenders, and other railway vehicles.

It is at present customary in railroad practice to equip engine trucks with floating or laterally movable bolsters and rocker bearings for the purpose of reducing the wear on the driving wheel flanges and the strain on the frame when the locomotive is moving around a curve. Various types of rocker bearings have been developed in which the degree of resistance to lateral movement of the bolster, determined with reference to the vertical load, remains constant. Some difficulty has been met, however, especially in high speed electric locomotives, in providing a sufficiently high initial resistance to maintain the proper stability when the locomotive is running on straight or slightly curved track at high speed, while, at the same time, providing for a low resistance when the locomotive is running at low speeds on a sharp curve in the railroad yards.

The main object of my present invention is to construct a rocker centering device which will overcome these difficulties. I attain this general object and others, later appearing, in the structure illustrated in the accompanying drawings in which—

Figure 1 is a vertical transverse section taken on the transverse center line of a locomotive truck embodying my invention.

Figure 2 is a vertical longitudinal section taken on the longitudinal center line of the same.

Figure 3 is a top view showing one of the rockers.

Figures 4, 5 and 6 are detail views corresponding with Figure 1 and showing successive positions of the rocker as the bolster moves laterally of the frame.

The truck frame is of familiar construction and includes box-shaped side members 1 tied together at each end by transverse members 2, and intermediate transoms 3 having connecting yokes 6 depending therebetween. The frame is carried on the journals 50 by any suitable spring equalizer system in-

cluding equalizer bars 10 shown in Figure 1.

The load from the locomotive is carried directly upon a center bearing 7 formed integrally with swing bolster 8 which is supported from the yokes 6 through a rocker centering device to be described later. The bolster is free to move laterally between transoms 3 which serve as guides. All of the structure above mentioned, except the rocker centering device, is similar to that described in Patent No. 1,060,222, issued to W. E. Woodward, April 29, 1913.

The rockers are counterparts and each is composed of an I-shaped body portion 11, end cams 14, and segmental journals 12 and 13 which normally rest within arcuate depressions 15 formed in a renewable rocker seat 9 provided on yoke 6. Each rocker cam surface is described upon the same center as the bearing surface of the opposite segmental journal. Bolster 8 has curved bearings 16 on its lower surface, each of which rests on the convex upper surface of the corresponding end cam 14. Links 19 and 20 are each pinned at one end to a lug 18 depending from the center plate portion of bolster 8 and at the other end secured to lugs 17 extending upwardly from the body portions of the rockers. These links hold the rockers in fixed relation to each other when the bolster moves laterally and irrespective of slippage which might otherwise occur between the bolster and the rockers.

The curvature of the lower surfaces of the bearings 16 are preferably identical, as are the upper convex edges of cams 14, and each bearing surface includes a central concave portion, that is, a portion of increasing slope of curvature, and outer portions of decreasing slope at each side thereof. The rockers and bearings are so arranged as to offer a high resistance to initial lateral movement of the bolster, a slightly higher resistance after a lateral displacement of the bolster of approximately one inch, and a rapidly decreasing resistance during continued displacement of the bolster in the same direction. The relative resistances at bolster displacements of one inch, three inches, and six inches from the normal rest position shown

in Figure 1 are indicated graphically in Figures 4, 5 and 6 by the distances x , y and z which are the horizontal components of the turning moments in each case. The resistance at rest is 35% of the load; at a displacement of one inch, 40%; at three inches, 25%; and at six inches 10%.

This arrangement provides a high resistance when the locomotive is traveling on straight track at high speeds and a low resistance when traveling on sharp curves in the yards. The low resistance will reduce the flange wear on the wheels. The theoretical desired resistance when the locomotive is on a straight track would be a greater resistance than the desired resistance when the locomotive is on a curve. However, since the friction for starting lateral displacement is very high, the device is designed for an initial resistance less than that attained after a slight displacement.

The essential features of the invention may also be embodied in a rocker centering device for connecting the locomotive underframe with a leading or trailing truck of the radial type in which there is no swinging bolster and each rocker cam would constitute a separate element. Moreover, the device might be modified for application to any two vehicle frame members capable of relative lateral movement and varied as to various details without departing from the spirit of the invention and I contemplate the exclusive use of all such variations as come within the scope of my claims.

I claim—

1. A rocker centering device for railway vehicles comprising a rocker and a rocker bearing mounted respectively on vehicle members capable of relative lateral movement, said bearing being inclined downwardly and outwardly on each side of the center thereof, the inclinations being steeper near the center of the bearing than near the outer ends thereof.

2. In a railway truck, the combination of a frame, a bolster adapted to move laterally relative thereto, and a rocker supporting said bolster from said frame, there being a bearing on said bolster for engagement with said rocker and having a surface inclined downwardly and outwardly on each side of the transverse center line of the bearing, the inclinations being steeper near the center of the bearing than near the outer ends thereof.

3. A rocker bearing device for railway vehicles comprising a rocker having spaced segmental journals on one side and convex cam surfaces opposite said journals, and a bearing surface opposed to said rocker, said surface comprising a central concave portion for engaging the intersection of said cam surfaces and convex side portions approaching the horizontal near the ends thereof.

4. A rocker centering device for railway

vehicles comprising a rocker and a rocker bearing mounted respectively on vehicle members capable of relative lateral movement, said rocker and bearing engaging along surfaces of different curvatures, the engaging surface of said bearing including a concave central portion and outer portions of decreasing slope at each side thereof.

5. A rocker centering device for railway vehicles comprising a rocker and a rocker bearing mounted respectively on vehicle members capable of relative lateral movement, said rocker and bearing engaging along surfaces of different curvatures, the engaging surface of said bearing including a concave central portion and outer portions of decreasing slope at each side thereof, and said rocker and bearing being arranged to offer a high resistance to the initial lateral displacement of said members, a slightly higher resistance after a small lateral displacement, and a comparatively low resistance after additional displacement.

6. A rocker centering device for railway vehicles comprising a rocker and a rocker bearing mounted respectively on vehicle members capable of relative lateral movement, the bearing surface of said rocker being convex and the engaging surface of said bearing being curved and including a central concave portion and an outer portion of decreasing slope.

7. A rocker centering device for railway vehicles comprising a rocker and a rocker bearing mounted respectively on vehicle members capable of relative lateral movement, the bearing surface of said rocker being convex and the engaging surface of said bearing being curved and including a central concave portion and an outer portion of decreasing slope, and said device being arranged to offer increasing resistance during initial relative displacement of said members and decreasing resistance after a certain point has been reached.

8. In a railway truck, the combination of a frame, a bolster adapted to move laterally relative thereto, and a rocker supporting said bolster from said frame, said rocker and bolster engaging along curved surfaces, the engaging surface of said bolster including a concave central portion and portions of decreasing slope at each side thereof, and said rocker and the engaging surface of said bolster cooperating to offer a high resistance after a small lateral displacement of said bolster, and a comparatively low resistance after additional displacement thereof.

9. In a railway truck, the combination of a frame, a bolster adapted to move laterally relative thereto, and a rocker supporting said bolster from said frame, said rocker and bolster engaging along curved surfaces, the engaging surface of said bolster including a central concave portion and outer portions of de-

creasing slope, and said rocker and the engaging surface of said bolster cooperating to offer a resistance to initial lateral movement of said bolster of approximately 35% of the load thereon, a resistance of approximately 40% of the load after a small lateral movement of said bolster, and a resistance of approximately 10% of the load near the extreme lateral movement of said bolster.

10 In testimony whereof I hereunto affix my signature this 27th day of January, 1931.

JAMES C. TRAVILLA, Jr.
